UNITED STATES PATENT OFFICE.

CHARLES R. OTIS, OF YONKERS, NEW YORK.

ELEVATOR.

SPECIFICATION forming part of Letters Patent No. 390,033, dated September 25, 1883.

Application filed February 18, 1883. Serial No. 264,529. (No model.)

To all whom it may concern:

Be it known that I, CHARLES R. OTIS, a citizen of the United States, residing at Yonkers, Westchester county, New York, have invented 5 certain new and useful Improvements in Elevators, of which the following is a specification.

My invention relates to that class of elevators in which the movement of a valve through 10 the medium of devices controlled from the cage or platform is the means of stopping and starting the cage, and especially of that class in which electromotors are employed in connection with the valve-actuating devices; and 15 my invention consists in means, fully set forth hereinafter, for preventing the shocks and strains usually resulting from the sudden opening and closing of the main valve.

In the accompanying drawings, Figure 1 is 20 an elevation of a hydraulic elevator embodying my improvements. Fig. 2 is an enlarged vertical section of the elevating-engine. Fig. 3 is a sectional elevation illustrating my invention in connection with an elevator-engine 25 in which the valve is shifted directly by hand.

In those classes of machines or engines in 30 which it is desirable to operate the controlling-valves from distant points—as elevators—and where such valves are actuated by electricity, the engines are frequently subjected to severe 35 strains from being abruptly stopped and started, the controlling-valves being shifted by single quick movements, at once fully opening or closing the ports, and bringing the full force of the motor-fluid suddenly upon or 40 cutting it off from the main piston.

Thus in the hydraulic elevator illustrated 45 in Figs. 1 and 2 the main-piston valve E in the valve-chest D controls the flow of motor-fluid to and from the cylinder A, containing the main piston B, the rod of which is connected with the cage C by flexible suspensories a. The valve E is moved by an auxiliary engine, G, having a cylinder, b, piston d, connected with the valve E by a stem, p, valve-chest g, and valve e, controlling the flow of motor-fluid from a supply-pipe, h, and thereby controlling also the shifting of the main valve.

As shown, the valve e is a rocking valve, 50 and an arm, f, on the valve-stem is connected to a spider carrying a series of cores, i, of solen-

oids I, electrically in circuit with a battery, and with conductors leading to the cage C, where a suitable switch, J, serves to make or break the circuit through the wires to excite 55 or discharge the solenoids, and thereby change the positions of the cores and of the valve e, connected therewith. Thus the solenoids are double, each consisting of two sections, 3 and 4, and by exciting the sections 3 the cores 60 are lifted to shift the valve and put the upper part of the cylinder b in communication with the supply-pipe to depress the piston d. By exciting the lower sections, 4, the cores are depressed to reverse the valve and put the 65 lower part of the cylinder in communication with the supply and raise the piston d, and by exciting both sections 3 4 the cores are carried to central positions with both coils, and the valve is set to cut off the flow of motor-fluid 70 and arrest the piston. The sections are in line with a battery, Z, and a circuit may be completed to include the battery and either or both sections through wires 5 6 7 by shifting the switch J in the car C so as to connect with 75 a terminal, 9, of the wire 7, the terminal 10 of the wire 6, or two terminals, 10 and 11, of both wires.

It will be seen that each movement of the cores is instantaneous, so that the valve e is 80 either opened, closed, or shifted by a single impulse, and the pressure of the motor-fluid is thrown on or off so suddenly as to produce sudden shocks, which are very disagreeable to passengers in the cage and detrimental to the 85 machinery. To obviate these objections to the use of electrical valve-moving devices, I combine therewith a valve or cock, which I term a "regulating-valve," which is arranged to gradually throttle or open a passage for the 90 motor-fluid prior to arresting or starting the engine, so that the full force of the said fluid cannot be brought into action until the engine has moved the cage for a short distance in one direction or the other, nor can it fully 95 cutoff until the movement of the cage is greatly reduced, thus preventing shocks and strains which would otherwise result.

The regulating-valve is shown as a damper-valve, n, arranged in the pipe h, so as to nearly 100 close the same when moved to a transverse position, permitting a slight flow of motor-

fluid, however, sufficient to start the engine when the valve *e* is opened.

The valve *n* occupies its transverse or closed position when the valve *e* is closed and the engine *G* is at rest, but is connected with the piston *d* or other moving part of the engine, so as to be opened after the piston has moved to a slight extent in either direction from its central position, and also to gradually close as the said piston approaches a middle position. Different connecting means may be employed, that shown consisting of a rod, *q*, extending from the piston *d* through the head of the cylinder *b*, and carrying the pivot of an arm, *r*, pivoted at its other extremity to the end of a pendent arm, *s*, fixed on the stem of the valve *n*. When the valve *n* is closed, the arm *s* will be vertical and the arm *r* occupy a horizontal position, and if the end pivoted to the rod *q* rises or falls the valve *n* will be gradually opened.

As shown in the drawings, the main valve *E* closes the outlet-port 19 from the main cylinder, and the main engine is at rest, but the operator in the cage has shifted the switch *J* to the contact 9, and the cores have been drawn down and the valve *e* shifted to throw the motor-fluid below the piston *d* to lift the valve *E*.

Instead of the sudden upward movement of the piston *d* and valve *E*, and the equally sudden uncovering of the port 19, the valve *n* so throttles the supply-pipe *h* that but a small volume of motor-fluid can pass to the cylinder *b* and the piston *d* starts but slowly; but after a short movement of the piston *d* the draft of the arm *r* on the arm *s* swings the latter outward until the valve *n* is opened and permits the free flow of the motor-fluid, the valve *E* being then quickly and freely lifted to open the port 19. If now it is desired to close the port 19, the operator shifts the switch *J* to the contact 10, and the cores are lifted and the valve *e* turned to carry the pressure to the top of the piston *d*, when the latter will be depressed; but before the valve *E* closes the port 19 the arm *r* will swing in the arm *s*, and the valve *n* is shifted so that the motor-fluid is almost entirely cut off as the valve *E* is brought to a position to close the port 19, and the final part of the movement is made so gradually that the engine is brought to a stop without any shock. The same results ensue if the valve *E* is moved downward to open the connection between the ports 19 20.

It is not essential to place the regulating-valve in the pipe *h*, supplying the motor-fluid to the auxiliary engine. It may be put in the main pipe *h'*, supplying the motor-fluid to the main cylinder, as shown in dotted lines, Fig. 2, the valve being shifted by two bearings, *r' r'*, through the medium of a lever, *u*, and connecting-rod *u'*. The effect is the same in each case.

While I have illustrated and described my regulating-valve in connection with an auxiliary engine and with electrical valve-shifting

devices, it will be evident that it may be effectively used to prevent shocks and strains if the main or auxiliary valves are shifted in any other way. Thus in Fig. 3 the valve *n* 70 in the pipe *h'* is arranged to be shifted by the movement of the stem of the main valve, connected to be operated, as usual, by a hand-rope extending to the cage.

Without limiting myself to the precise construction and arrangement of parts shown, I claim—

1. The combination, with the main valve and the electric valve-operating devices of an engine, of a regulating-valve for said engine, 80 controlling the flow of the motor-fluid thereof, and connected with the main valve, to throttle the flow of motor-fluid as the main valve approaches or moves from a closed position, substantially as described.

2. The combination, in an elevator-engine, of a main valve, a regulating-valve therefor arranged in a supply-pipe and connected with the main valve, and an auxiliary valve-operating engine provided with a valve connected with an electric motor, substantially as described.

3. The combination, with an electrically-controlled valve of an elevating-engine, of a regulating-valve therefor in a passage for the 95 motor-fluid thereof, and a main valve connected with the regulating-valve to shift it, substantially as described.

4. The combination, in an elevator, of the main engine provided with a valve, an auxiliary engine connected to operate the main valve, an electromotor connected to the valve of the auxiliary engine, and a regulating-valve controlling the flow of motor-fluid to the auxiliary engine and connected with the main 105 valve, substantially as described.

5. The combination, with the cylinder and piston of an elevator-engine, and with a valve controlling the movements of said engine and connected with the cage to be operated therefrom, of a regulating-valve in a supply-pipe for said engine connected with said controlling-valve, substantially as described.

6. The combination, with the piston and cylinder and main valve, and connections between the latter and cage of an elevator, of a supplemental valve in a supply-pipe for said engine connected to the main-valve-shifting devices to be operated therefrom to fully open the said pipe after the main valve begins to 115 open its port and close it before the main valve closes its port, substantially as described.

7. In an engine, a main stopping and starting valve therefor, a supply-pipe leading to 125 the engine, a regulating-valve therein, and intermediate connections between said valves, whereby both valves are simultaneously brought to a closed position, substantially as described.

8. The combination of an elevator-engine and its controlling-valve and a supply-pipe

for the motor-fluid of said engine, provided with a regulating-valve therein, connected with the main valve, substantially as described.

9. The combination, with the valve and auxiliary valve-operating engine of an elevator, of a regulating-valve controlling the supply to the auxiliary engine and connected with the main valve to be operated therewith, substantially as described.

10. The combination of the main engine and main valve of an elevator, an auxiliary engine, and a supply-pipe for said engine, and a regulating-valve therein connected with the main valve to move therewith, substantially as described, the arrangement being such as to gradually and automatically close the supply of motor-fluid to the auxiliary engine as the main valve takes its position to arrest the movement of the main piston.

11. The combination, with the elevator-en-

gine, of an auxiliary engine, the piston of which is connected with the main valve, a supply-pipe for said engine, and a regulating-valve therein connected to the piston-rod of the auxiliary engine, substantially as described. 25

12. The combination, in an elevator, of the main valve, supply-pipe, regulating-valve therein controlling the supply of motor-fluid and connected with the main valve to move therewith, and a main-valve-operating device 30 extending to the cage, substantially as described.

In testimony whereof I have signed my name to this specification in the presence of two subscribing witnesses.
